CLAIM

The ornamental design for a data recording/reproducing apparatus, as shown and described.

DESCRIPTION

FIG. 1 is a plan view of a data recording/reproducing apparatus showing our new design;

FIG. 2 is a bottom view thereof;

FIG. 3 is a front view thereof;

FIG. 4 is a rear view thereof;

FIG. 5 is a left side view thereof;

FIG. 6 is a right side view thereof; and,

FIG. 7 is a perspective view thereof.

FIG. 1

FIG. 2

FIG. 3***FIG. 4****FIG. 5*

FIG. 6

FIG. 7
